UNITED STATES PATENT OFFICE.

JUOZAPAS ATKOCAITIS, OF CHICAGO, ILLINOIS.

NECKTIE-PRESSING BOARD.

1,391,444.

Specification of Letters Patent. Patented Sept. 20, 1921.

Application filed May 7, 1920. Serial No. 379,641.

To all whom it may concern:

Be it known that I, JUOZAPAS ATKOCAITIS, a citizen of Lithuania, residing at Chicago, county of Cook and State of Illinois, have 5 invented certain new and useful Improvements in Necktie-Pressing Boards, of which the following is a specification.

My invention relates to improvements in necktie smoothing devices or ironing boards, 10 and manner of using the same.

It is the principal object of my invention to provide a device that is suitable for smoothing out the wrinkles in neckties.

A further object of the invention is to 15 provide a device of convenient dimensions which will stretch the tie to its original shape and will permit the wrinkles to be smoothed out prior to the ironing operation.

20 Another object of the invention is to produce a portable device for the purpose mentioned that is operated in a simple manner, and efficiently, with a minimum of attention on the part of the operator and which is especially adapted to allow an ironing of the 25 smaller as well as the larger part of for instance four-in-hand ties.

To this end the device comprises a pair of 30 separate wings, each of which is shaped to fit one end of the tie and to expand and stretch it.

In the accompanying drawing the invention is illustrated by way of example, and

35 Figure 1 shows a pair of tapered flat wings.

Fig. 2 is a top plan view of the device constructed according to the present invention and illustrating the manner of using the device.

40 Fig. 3 is a view similar to Fig. 2 illustrating the manner of securing both parts of a four-in-hand tie to their respective wings and boards.

Fig. 4 is a sectional view taken on line 45 4-4 of Fig. 2.

The larger of the wings is designated 10 and the smaller 11 both being provided at their smaller ends with prongs 12, 13 adapted to hold the parts of a four-in-hand necktie in place upon the wings.

50 As shown in Fig. 2 the larger part 14 of the necktie is recessed and drawn over the

smaller part 15 upon its wing 11 while the lining 16 of the larger wing is shown broken off.

55 In Fig. 3 the lining 16 is shown engaged by the prongs 12 of the larger wing 10 doubled up and drawn underneath of the large wing 10, to which the larger part 14 of the necktie is clamped by clamps 17, 18 while 60 the small wing 11 is placed on top of the inner face of part 14 and the smaller part 15 rests upon the wing 11 while its lining 19 is drawn around prongs 13 to cover the underside of the small wing 11.

65 It will be clear that the wings in this manner are thrust in the ends of the ties to be flattened out, and if this operation is performed every time after the tie has been used the tie will be kept in good order and 70 will be easily smoothed with a pressing iron.

The wings may be made of any suitable material and changes may be made in the form and size without materially departing from the scope and spirit of my invention.

75 Having thus described my invention what I claim as new and desire to secure by Letters Patent of the United States is as follows—

1. A tie stretching and pressing device 80 comprising a pair of wings, one larger than the other, prongs on each of said wings, the larger wing adapted to support the larger end of a tie and its prongs adapted to engage the lining of said larger end, the shorter wing adapted to support the smaller end of the tie and its prongs to engage the lining of said smaller end and clamping means for clamping the tie to said wings.

85 2. A tie stretching and pressing device of 90 the character described, comprising a smaller and a larger wing, prongs at the smaller end of each of said wings, said prongs adapted to engage the lining of a tie, the larger wing adapted to support the larger 95 end of a tie and the smaller wing adapted to be placed within said larger tie end and to support the smaller end of a tie substantially as described.

100 3. A tie stretching, smoothing and pressing device of the character described, comprising a smaller and a larger wing of oblong shape, a plurality of prongs at the smaller end of each of said wings, said

prongs adapted to engage the lining of a tie, the prongs of the smaller wing the lining of the smaller part of the tie, and the prongs of the larger wing the lining of the larger tie part, the small wing and tie part adapted to be placed upon the larger wing to support the ironing process, and means

for clamping the larger part and the smaller part upon said larger wing, substantially as described.

In testimony whereof I have affixed my signature.

JUOZAPAS ATKOCAITIS.
